(57) CLAIM

I claim the ornamental design of the fruit scoop, as shown and described.

DESCRIPTION

FIG. 1 is a perspective view of a fruit scoop;
FIG. 2 is a top view of a fruit scoop;
FIG. 3 is a bottom view of a fruit scoop;
FIG. 4 is a front view of a fruit scoop, the back view being substantially identical to the front view; and,
FIG. 5 is a left side view of a fruit scoop, the right side view being substantially identical to the left side view.
